UNITED STATES PATENT OFFICE

2,052,356

ASSEMBLY MACHINE

Leland E. Long, Ardmore, Ind., assignor to The Lubrication Corporation, Chicago, Ill., a corporation of Delaware

Application July 3, 1933, Serial No. 673,892
Renewed November 29, 1935

22 Claims. (Cl. 29—33)

This invention relates to improvements in assembly machines and more particularly to machines for automatically assembling lubrication fittings, or nipples, of the type commonly employed on a motor vehicle chassis or upon stationary machinery, for receiving lubricant from a lubricating gun or other similar lubricant feeding apparatus.

While a lubricant receiving fitting of the spherical headed type is shown within which a valve, a valve spring and a spring retainer may be assembled by the machine, it should be understood that many other types of fittings, varying as to body contour, may be assembled by the machine and that the term "fittings" shall be hereinafter used in its generic sense as comprehending various types of lubricant receiving fittings regardless of body contour.

One of the primary objects of the invention is to provide a machine of the character indicated which will automatically handle the fittings and valves, and which will automatically form and handle the valve springs and spring retainer members to assemble and permanently secure the several elements in their proper operative relationships, and one which will be fast and reliable in operation as well as entirely automatic as to its joint and several functions so as to relieve the operator of any manual manipulation other than to keep the machine supplied with material and to remove the completed product when ejected from the machine.

With these general aims in view, the invention contemplates a machine which will automatically remove fittings from a hopper and feed them out at a time, in inverted position, upon an intermittently rotated turret-like table, where they may be carried upon the table to the where they may be carried upon the table to the next or second station. At the second station the machine supplies valves from a hopper and automatically feeds them one at each progressive movement of the table into the fitting previously placed upon the table. Further table movement carries the fitting and valve to the third station where valve springs are formed, one at each table movement, and automatically fed into the fitting shank over the valve. From this station the partially assembled fitting is moved by the table to the fourth station where a spring retainer is automatically formed from the length of steel wire and fed over the spring and inverted fitting shank and subsequently welded across the end of the shank to permanently support and confine the valve and spring within the fitting bore. At

a fifth station located between the first and fourth stations, the completely assembled fitting is automatically ejected from the machine, through the medium of an air jet, where it may fall into a suitable receptacle provided therefor.

A preferred embodiment of the invention is illustrated in the accompanying drawings in which:

Fig. 1 is a left side elevation of a machine incorporating the features of the invention. 10

Fig. 2 is a front elevation of the machine illustrated in Fig. 1.

Fig. 3 is a right side elevation of the machine.

Figs. 15 to 18 inclusive represent the fitting as it appears at the termination of the operation at stations one, two, three and four respectively, and,

Fig. 19 is a sectional view through the valve 40 feeding mechanism.

The driving means

Referring now to the drawings and particularly to Figs. 1 to 5 inclusive, it will be observed 45 that the machine is constructed upon a base or bed 15 intended to rest directly upon the floor and that the apparatus for feeding the blank fittings and the apparatus for feeding the valves are mounted upon columns 16 and 17 respectively 50 mounted upon the base 15. A platform 19 is located above the bed 15 and directly under the turret-table 21 and serves to support the apparatus for forming and delivering the valve springs and the apparatus for forming the spring re- 55

tainer. The welding apparatus is mounted upon the bed 15 and includes a vertically extending supporting casting 22 which serves also to lend support to the platform 19.

5 The apparatus for delivering the fitting blank to the table 19 is driven by an electric motor 25. The valve feeding apparatus is likewise operated, independently, by an electric motor indicated by dotted lines at 26 in Fig. 1. The balance of the 10 machine including the table 21 is driven by an electric motor 27 supported upon the bed 15 and having driving connection with a main horizontal drive shaft 28 through a reduction drive unit 29, pinion and gears 31 and 32 respectively and 15 a manually operable clutch 33. The clutch 33 may be manipulated by a hand lever 34 at the front of the machine.

The drive shaft 28 extends through a housing 35 within which the lower end of a vertical shaft 36 is located. The upper end of the vertical shaft 36 is axially aligned with a shaft 37, to the upper end of which the table 21 is fixed. The ends of the shafts 36 and 37 are feathered to one another by plates 38 and 39 respectively so as to permit 25 the table 21 and shaft 37 to be moved vertically along the axis of the shaft without disturbing its driving connection with the lower vertical shaft 36.

A circular plate 41 is fixed to the lower end of 30 the shaft 36 within the housing 35 and has supported thereupon, adjacent to its periphery and on its lower face, eight rollers 42 equally spaced from one another and each provided with roller bearings 43. The eight rollers 42 bear the same 35 relationship about the axis of the shaft 36 as do the eight fitting receiving receptacles 44 fixed to the upper surface of the table 21 and located at equal distances apart from one another. A cam wheel 45, mounted upon the shaft 28 within the 40 housing 35, is arranged to engage with the rollers 42 of the plate 41 so that at each revolution of the shaft 28, the table 21 will be driven through the shafts 36 and 37 one-eighth of a revolution, or throughout an arc of forty-five degrees. The 45 cam 46 of the cam wheel 45 is so constructed as to cause rotational movement of the table 21 throughout one hundred degrees of rotation of the shaft 28 thereby leaving two hundred sixty degrees of main shaft rotation wherein no movement of the table may occur.

A vertical shaft 48 located at one end of the main shaft 28 and having driving connection therewith through beveled gears 49 and 51 respectively is provided for the purpose of driving 55 the spring forming apparatus of the machine. An eccentric cam 52 is fixed to the opposite end of the shaft 28 and is employed to elevate a push rod 53 for operating the welding electrodes of the spring retainer welding apparatus once during 60 each revolution of the main shaft. A second cam 54 is mounted upon the shaft 28 adjacent to the cam 52 for the purpose of actuating the welding current switch as will be hereinafter explained.

65 *Handling the blank fittings*

Referring now to Figs. 7 to 10 inclusive, the blank fittings as shown in Fig. 15 are initially fed to the machine by disposition within a metal hopper 61, substantially V-shaped in cross sectional contour, as shown in Fig. 10. The hopper is provided with a slot 62 extending along the bottom of the V. No care need be exercised in placing the fitting blanks within the hopper as the fitting handling apparatus operates to 75 select only those fittings which are lying parallel

to the slot 62 with their shanks inclined downwardly as indicated in dotted lines at 63 in Fig. 9. An endless chain conveyer 64, mounted upon sprockets 65 and 66 respectively, is located beneath and parallel with the slot 62 of the hopper. The chain may be driven through a gear 67 in mesh with a pinion 68 driven by the motor 25 through a reduction gear unit 69. The entire assembly including the hopper 61 may be mounted upon a frame 71 supported, as previously described, upon the column 16.

A plurality of fingers 72 are supported at spaced distances from one another on the outermost side of the chain 64. Each of the fingers 72 has a pin 73 fixed thereto of a diameter slightly less than the bore 74 of the shank 75 of the fitting blank (see Fig. 15), and of sufficient length to enter the bore 74 and to support the fitting blank as indicated in dotted lines in Fig. 9. Inasmuch as a plurality of the fitting blanks may be expected at all times to lie adjacent to the groove 62 and parallel therewith, those having their shanks extending downwardly may be readily engaged by the pins 73 of the fingers and thus carried upwardly out of the hopper 61 and into a delivery tube 76 where they may fall through the tube into an automatic feeding device 77 including a plunger 78 adapted to reciprocate once during each revolution of the main shaft 28 to convey a fitting blank from the position shown at 79 in 30 dotted lines of Fig. 9 to a position overlying a bore 81 immediately over a fitting receiving receptacle 44 on the table 21. The plunger 78 (see Fig. 1) is operated through a push rod 82, a rocker arm assembly 83, and a roller and cam 84 and 35 respectively located upon the rocker arm and vertical shaft 48 respectively.

In order to assure the constant feeding of the fitting blanks to the table, one at each progressive movement of the table, the hopper 61 is preferably constructed with that portion parallel to the chain 64 slightly longer than is necessary according to the law of averages as applied to the probable number of fittings which will become engaged by the fingers 72 as the chain operates. 40 This condition, however, necessitates that some safeguard be provided to prevent the apparatus from becoming jammed, should the tube 76 become filled. To this end the tube 76 is severed and parted at 87 so that the fittings must drop 50 from the upper part of the tube 76 to the lower portion 88 thereof. A receptacle 89 fixed to the outer wall of the portion 88 of the tube serves to catch any fittings which may fail to pass into the lower portion of the tube by virtue of its becoming filled with fitting blanks awaiting delivery to the table through the mechanism 77. 55 If desired, the receptacle 89 may have an opening 91 through its bottom wall so that the fitting blanks may fall into an overflow receptacle to be 60 subsequently replaced in the hopper 61.

The upper end of the hopper is formed with a flat bottom wall 92 and with substantially vertical side walls 93, thus providing a V-shaped opening 94 between the upper and the low portions of the hopper so that fitting blanks carried into the upper portion of the hopper along with those engaged by the fingers 72 may, in sliding back into the lower part of the hopper, move along a path and in a position which will promote their operative engagement with the pins 73 of the fingers 72, thus increasing the efficiency of the fitting handling apparatus.

In operation the apparatus described will, at each revolution of the main shaft 28, deliver 75

one of the fitting blanks into the adjacent of the fitting receptacles 44 upon the table 21. The cam 85 is so placed upon the shaft 48 as to cause delivery of the blank fitting to take place when the table is at rest.

Handling the valves

The valves 95, one of which is shown in detail in Fig. 16, are placed in the machine by disposition in a hopper 96 where they are automatically fed, with the inverted stem portion 97 extending downwardly, along a slotted slide way 98 from the hopper into a feeding device 99 similar in operation to the feeding device 77 shown in Fig. 9 and having a plunger 101 operated through a link 102 by the rocker arm assembly 83. The valves are delivered to the receptacles 44, one at each forty-five degree rotational movement of the table 21 so that they may fall into the fitting previously placed in the receptacle and assume the position shown in Fig. 16. In order that the valves may be placed in sufficient quantities upon the slide-way 98, a pair of oscillating segmental arms 103 are mounted one on either side of the slide-way 98 and pivotally mounted at their lower ends 104. A crank arm 105 mounted at the lower ends 104 of the arms is arranged to be reciprocated by a pitman 106 through an eccentric drive gear, not shown, which in turn is driven by the motor 26. The slot 107 extending longitudinally of the slide-way 98 is of such a width as to admit only the inverted stem portion 97 of the valve, thus assuring that the valves after once becoming placed upon the slide-way will ride along the slide-way with the stem extending through the slotted or inner portion in the manner indicated in Fig. 19. The uppermost edges of the arms 103 may be beveled at substantially 45°, as shown at 108, so as to insure the transfer of the valves to the slide-way when the arms are elevated.

Forming and handling the valve springs

A standard spring forming machine 111 of the type commonly employed for forming small wire springs such as shown at 112 in Fig. 17 may be employed for forming the springs to be used in urging the valve 95 against its seat 113 in the body of the fitting. This machine is supported upon the table 19 and is synchronized with the drive shaft 28 through the medium of a bevel ring gear 115 carried by the shaft 48 engageable with a bevel gear 116 mounted upon the drive shaft 117 of the spring forming machine. The ratio between the gears 115 and 116 is such as to cause the spring forming machine 111 to form one complete spring at each revolution of the vertical shaft 48. A tube 118 may be employed to conduct the finished spring from the machine 111 to that receptacle 44 which is, at the time, located ninety degrees from that into which a valve 95 was last dropped. In order that the valve spring forming machine may be adjusted so that the finished spring will be delivered at the proper time, a pair of adjusting nuts 119 is provided to permit of the adjustment of the bevel ring gear 115 relative to the shaft 48. Further, a driving lock pin 121 is employed to permit of the disengagement of the gear 115 from the shaft 48 so that the spring forming machine may be operated independently of the balance of the assembly machine, as during adjustment, but wherein pre-established synchronism between the spring forming machine and the shaft 28 may not be impaired. This latter feature is made

possible by the provision of but one socket 122 within which the pin 121 may fall in effecting driving engagement between the ring gear and the shaft 48.

Initial formation of the valve spring retainer

The valve spring retainer (see Fig. 18) comprises a short length of steel wire 114 extending across the end of the shank 15 and welded thereto at opposite ends as indicated at 120. To assure the severing of a short length of wire from a roll of wire stock, the wire stock indicated at 123, in Fig. 12, is fed between a wheel 124 having a plurality of spaced apart steel notching teeth 125 and a hardened steel roller 126. The wheel 124 is mounted upon a shaft 127 which in turn is rotatably supported upon a body casting 128 resting upon the table 19. The roller 126 is rotatably mounted upon a shaft 129, the opposite ends of which are disposed in pillow blocks 131 held against movement away from the wheel 124 by adjustable set-screws 132. Compression springs 133 may be employed to urge the blocks yielding against the screws 132. A worm wheel 134 is fixed to the opposite end of the shaft 127 and driven by a worm not shown located upon a vertical shaft 135. A pinion 136 is located upon the shaft 135 and keyed thereto through the medium of a pair of opposed notched grip plates 137 and 138, one secured to the shaft 135 and the other to the pinion 136.

The pinion 136 is in mesh with the gear 139 mounted upon the upper end of a shaft 141 rotatably mounted upon the sleeve 142. The gear 143 mounted upon the shaft 141 at the lower end thereof and connected with the shaft 141 through a pair of grip plates 144 and 145 similar to the plates 137 and 138 is in mesh with a ring gear 146 carried by the shaft 36. The notching wheel 124 is thus caused to advance a predetermined distance during each movement of the table 21. The distance advanced is that equal to the distance between two adjacent notching teeth 125.

With reference to Fig. 11, it will be seen that the wheel 124 is composed of two longitudinally divided parts 149 and 150 with hardened steel teeth 125 clamped between them separable upon the removal of a nut 130. A ring 147 is employed to provide a circumferential abutment against which the inner ends of the teeth 125 may rest. As the teeth become worn, the ring 147 may be replaced with one of larger external diameter thereby greatly increasing the life of the notching teeth which may be expected to become worn extensively through use. In like manner, the hardened steel roller 126 is in the form of an annulus fixed to cast plate 148 thereby permitting the replacement of the work engaging portion of the roller whenever necessitated, as through wear.

The wire 123 is conducted between the wheel 124 and the roller 126 through a tube 151 and after passing between the wheel and roller as during the notching operation the notched wire is further conducted through a tube 152 to a point 65 over that one of the receptacles 44 that is at the time in registration with the welding electrodes (see Fig. 14).

Welding the spring retainer

Subsequent to the stopping of the table 21 thereby to cause registration of an inverted fitting blank with valve and spring in place with the welding electrodes, the cam 52 is caused to operate to elevate the push rod 53. As the push rod is 75

elevated a rocker arm 154 pivotally mounted at 155, intermediate its length, and pivoted at one end 156 to the upper end of the push rod, is caused to move upon its axis and to depress the 5 upper electrode assembly 157. Simultaneously a shoe 158 located on the lower end of a pusher rod 159 is caused to move downwardly under the force of a compression spring 161 and to depress the table 21 which normally floats under the influence 10 of a compression spring 162 in that position indicated in Fig. 13. The pusher rod 159 is connected by horizontal arm 163 to the upper electrode assembly 157. As the table 21 is depressed in the manner described a copper contact member 164 15 mounted upon the lower face of the support 165 upon which the receptacle 44 is located is urged into contact with a stationary contact shoe 166 or electrode carried by a horizontal support bar 167 adjustably mounted at 168 to the supporting 20 casting 22. The upper electrode 169, under the influence of the push rod 53 as described, is simultaneously caused to descend and to engage with those portions of the notched wire which overlie diametrically opposite portions of the inverted 25 end of the shank 75 of the fitting blank. At the time at which contact under thrust between the welding electrodes and fitting assembly is established the cam 54 (see Fig. 3) is caused to engage with and operate a switch arm 171 of a switch 30 172 included in series in the secondary electrical circuit 160 of the welding transformer shown in Fig. 4 thereby to conduct current induced from the transformer primary 153 to the electrodes. Included in series with the switch 172 is a second 35 switch 173 that is normally closed when the hand lever 34 operating the main shaft clutch 33 is in that position to cause the clutch to engage. If, however, the lever 34 is moved to a position to cause the clutch to become disengaged the lever 40 34 will contact with the push button 174 of the switch 173 to open the welding circuit. It is thus impossible for one to shut down mechanical operation of the machine by opening the clutch 33 without also shutting off the welding current so 45 that the hazard of serious damage to the electrodes and table 21 through the passage of welding current therethrough for an undue duration of time is obviated.

The upper electrode 169 of the welding apparatus is, as shown in Fig. 14, formed somewhat after the fashion of centering pin of a lathe so that it may be removed at will from its supporting cylinder 177 for replacement or repair. Means for cooling the upper electrode is provided for in a 50 water circulatory system including an inlet pipe 178 and an outlet pipe 179, in combination with a circulating tube 181 located within the cylinder 177, so as to direct incoming water upon the inner end 182 of the bore of the electrode after which it 55 is removed through the pipe 179. In like manner the lower electrode 166 is cooled by a water circulating tube 183 adapted to convey water up into the bore 184 of the lower electrode.

Ejecting the completed fitting

The welding operation at the fourth station about the table 21 represents the final operation in the assembly and permanent retention of the valve and spring within the fitting blank. At the 60 next table movement the completed fitting from the fourth station is carried on the table through an arc of 45° to the ejecting or fifth station where air, admitted through a tube 185 in registration with a bore 186 extending through the block 165 65 and receptacle 44, is caused to forceably eject the 70 75

completed fitting from the receptacle and from the table where it may fall into a suitable receptacle provided therefor. A valve 187 in the air tube 185 is caused to operate to admit air to the bore 186 at the termination of each table movement by means of a star cam 189 secured to the underside of the table 21 and engaging at its periphery with the valve stem 191 of the valve. 5

It is believed that the construction and operation will be understood from the foregoing description of what is, at present, the preferred form of the invention. Of course, various changes and modifications in construction and operation may be made and may result in a machine bearing little resemblance to that illustrated. Therefore, 10 it is not desired to be limited to the details of construction illustrated and described but only by the spirit of the invention and the scope of the appended claims. 15

What I claim is:

1. In a machine of the character described, the combination of a table adapted for cyclatory movement, a plurality of means spaced about said table at predetermined distances apart from one another for depositing a fitting having a bore therethrough and including a shank portion, a valve, and a valve spring respectively upon the table in predetermined sequence as the table progresses through its cyclatory movement, means for supplying a valve and spring retainer to the fitting, and automatic means including a plunger for pressing said retainer into engagement with said shank, and mechanism for securing the retainer to said shank thereby to render said fitting, valve, spring, and retainer assembly permanent. 20

2. In a machine of the character described, the combination of a table arranged for intermittent cyclatory movement, means for placing a blank fitting having a bore therethrough and including a shank portion upon the table, means for depositing a valve in the fitting bore, automatic means for forming and delivering a valve spring into the fitting bore, and means for permanently assembling the elements thus initially assembled, each 30 of said means being adapted to complete its respective function once for every intermittent movement of the table. 35

3. In a machine of the character described, the combination of an intermittently revolving table, means for feeding a succession of blank fittings, each having a bore therein, upon said table, means for feeding a valve and a valve spring successively into each of said fitting bores and means for fixing a valve and spring retainer to each fitting partially to close said bore permanently to assemble the parts, said feeding means and said retainer fixing means being arranged circumferentially about the table and operable during the intervals between table movements. 50

4. In a machine of the character described, the combination of a revolvable table having a plurality of receptacles located one in each of a plurality of equally divided sectors of the table respectively, means for supplying blank fittings, each having a bore therein, to the receptacles, and a plurality of means spaced about the table for delivering valves, valve springs and spring retainers in sequence to the blank fittings, said valve and valve springs being deposited in the bores of said fittings and said retainer being deposited across the mouth of said bores, each of said means having its delivery instrumentality in registration with one of said receptacles when 55 60 65 70 75 76

the table is at rest, and means including a continuously running motor for intermittently revolving said table a distance equal to one sector of the table.

5. An assembly machine of the character described comprising, a table adapted to support a plurality of blank fittings during the assembly of parts therein, driving means for intermittently and progressively rotating said table a fraction of a revolution, means for depositing a blank fitting on the table, means for depositing a valve in said blank fitting on said table, each of said depositing means being synchronized with said driving means and effective between table movements, means for placing a valve spring over the valve in said blank fitting, means driven by said driving means for pre-forming a spring retainer, and welding means for welding said retainer across the shank of the fitting to hold the valve and spring in place, said blank fitting, valve and spring depositing means and said welding means being each located at predetermined distances apart from one another about the periphery of said table.

10. 6. In a machine of the character described, the combination of means for successively feeding a plurality of fittings, means for assembling a valve within said fitting, and automatic means for forming a valve retainer for said fitting from a length of metal wire and for welding the retainer to the fitting.

7. In a machine of the character described, the combination of means for successively feeding a plurality of fittings, means for assembling a valve within said fitting, and automatic means for constructing a permanent valve retainer for said fitting from a length of metal wire, said last named means including a wire notching device and a welding mechanism for welding the wire across the base of the fitting transversely of the axis of the bore of the fitting.

8. In a machine of the character described, the combination of a work supporting table mounted for movement on a vertical axis, resilient means for holding said table in an elevated position, welding means including a relatively stationary electrode beneath the table and normally spaced apart therefrom, and a movable electrode above the table, and means for depressing the upper electrode and for simultaneously urging the table downwardly into engagement with the lower electrode.

9. In a machine of the character described, the combination of a work supporting table mounted for movement on a vertical axis, resilient means for holding said table in an elevated position, welding means including an electrode beneath the table and normally spaced apart therefrom, and a movable electrode above the table, means for depressing the upper electrode and for simultaneously urging the table downwardly into engagement with the lower electrode, and a switch for controlling the supply of current to said electrodes arranged to close the electrode circuit upon operation of said last named means as described.

10. In a machine of the character described, the combination of a table mounted for cyclatory movement, a motor, means including a clutch and an intermittent drive mechanism for intermittently and progressively moving said table throughout its cycle of operation, automatic means for assembling a fitting upon said table, welding apparatus for welding a portion of said fitting assembly when on said table during that time wherein the table is stationary, and means

included in the welding current circuit for opening the circuit when said clutch is disengaged, regardless of the position of the table.

11. In a machine of the character described, the combination of a table adapted for intermittent rotation, a plurality of fitting receiving receptacles carried by the table at equal distances apart from one another and from the axis of rotation of the table, means for assembling a fitting within said receptacles as the table moves throughout a cycle of its rotational movement, said receptacles in said table having aligned bores therethrough parallel to the axis of the table, an air jet adapted to register with said bores selectively as the table is rotated, and a valve for admitting compressed air to said jet operable upon registration of the jet with said bores to eject the completed fittings from the table.

12. In a machine of the character described, a hopper for receiving fittings having an aperture at the one end, means for conducting said fittings away from said hopper and means for transferring said fittings from said hopper to said conducting means in substantially axial alignment and with their apertured ends facing in one direction, said first named means including vertically aligned tubular members mounted with a gap therebetween, said gap being of a length greater than the length of a fitting, and a receptacle adjacent to the upper end of the lower tubular member and adjacent to said gap for the reception of fittings falling out of their normal path of movement at the gap.

13. In an assembling machine of the character described, the combination of a table adapted for cyclatory movement in a series of intermittent steps, means for driving the table and for indexing the table at the termination of each step in its intermittent travel, a plurality of guide means at predetermined positions along the path of movement of the table for guiding elements to be assembled under the force of gravity toward the table, and means synchronized with said indexing means for delivering said elements, one at a time, from each of said guide means upon the table after each indexing of the table, said last named means including members having openings transversely therethrough adapted to reciprocate across the path of said elements in said gravity guide means once for each indexing of the table.

14. In a lubrication fitting assembly machine in combination, a support, means for feeding blank lubrication fittings in succession to said support, each of said fittings having a bore, means for automatically feeding a valve and a valve spring into the bore of each fitting, and welding means operative automatically to secure the valve spring in each fitting.

15. In a lubrication fitting assembly machine in combination, a support, means for feeding blank lubrication fittings in succession to said support, each of said fittings having a bore, means for automatically feeding a valve and a valve spring into the bore of each fitting, and welding means automatically operable after assembly of a valve and valve spring with each fitting for securing the assembly together.

16. In a lubrication fitting assembly machine in combination, a support, means for feeding blank lubrication fittings in succession to said support, each of said fittings having a bore, means for automatically feeding a valve and a valve spring into the bore of each fitting, means for

supplying a valve spring retainer to each fitting, and means for fixing each retainer to its fitting against the exit of the spring from the bore thereof.

5 17. In a lubrication fitting assembly machine in combination, a plurality of fitting holders, means for feeding a blank lubrication fitting to each holder, each of said fittings having a bore providing a valve seat, means for inserting a valve in the bore of each fitting, and means for securing a retainer for each valve to each fitting.

10 18. In a lubrication fitting assembly machine in combination, a plurality of fitting holders, means for feeding a blank lubrication fitting to each holder, each of said fittings having a bore providing a valve seat, means for inserting a valve and a valve spring into the bore of each fitting, and means for welding a spring retainer to the fitting in the path of exit of the spring.

15 19. In a lubrication fitting assembly machine in combination, a plurality of lubricant fitting receivers, means for feeding a lubricant fitting to each receiver, each of said fittings having a bore providing a valve seat, means for feeding a valve and a valve spring into each fitting bore, and means operable after assembly of a valve and a spring with each fitting for securing the assembly permanently together.

20 20. In a machine of the character described, the combination of a table, means for feeding a succession of blank fittings, each having a bore, upon said table, automatic means for feeding a

valve and a valve spring into the bore of each of said fittings, means for supplying valve spring retainers, and means operable upon the assembly of said parts for fixing a spring retainer permanently to each of said fittings partially to close 5 the bore of each of said fittings.

21. In a machine of the character described, the combination of a table, means for feeding a succession of blank fittings, each having a bore, upon said table, automatic means for feeding a 10 valve and a valve spring into the bore of each of said fittings, means for supplying valve spring retainers, means operable upon the assembly of said parts for fixing one of said retainers permanently to each of said fittings partially to close 15 the bore of each fitting, and automatic means for ejecting the permanently assembled fitting from the machine.

22. In a machine of the character described, the combination of a work receiving table, means 20 for depositing a blank fitting in an inverted position upon the table, said fitting having a shank, a bore extending longitudinally therethrough, and an enlargement of the bore in the shank, a gravity conveyor for conducting a valve having 25 an elongated stem with said stem in vertical position into said fitting when the fitting is on the table, said conveyor means including a slide-way having a longitudinal slot therein, the slot being wider than the valve stem but of less width 30 than the body of the valve.
